CLAIM

The ornamental design for a TV antenna, as shown and described.

DESCRIPTION

FIG. 1 is a front perspective view of a TV antenna showing my new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a left side elevational view thereof;

FIG. 7 is a right side elevational view thereof; and,

FIG. 8 is a bottom plan view thereof.

The structural-features depicted by broken lines have been shown for the purpose of illustrating portions of a TV antenna that form no part of the claimed design.

1 Claim, 3 Drawing Sheets
